Specification for Design. Patented Mar. 28, 1922.

Application filed June 21, 1921. Serial No. 479,394. Term of patent 3½ years.

To all whom it may concern:

Be it known that I, WILLIAM F. LEBZELTER, a citizen of the United States, residing in Elizabethtown, county of Lancaster, and State of Pennsylvania, have invented a new, original, and ornamental Design for Toy Gliders, of which the following is a specification, reference being had to the accompanying drawing, which forms a part thereof.

The figure is a perspective view of a toy glider embodying my design.

I claim—

The ornamental design for a toy glider, as shown and described.

In testimony of which invention, I have hereunto set my hand, at Elizabethtown, on this 20th day of May, 1921.

WM. F. LEBZELTER.
